(57) **CLAIM**

The ornamental design for a mobile phone charger, as shown and described.

DESCRIPTION

FIG. 1 is a perspective view of a mobile phone charger, showing my new design;

FIG. 2 is a perspective view of the design in a use status;

FIG. 3 is another perspective view thereof;

FIG. 4 is a front view thereof;

FIG. 5 is a rear view thereof;

FIG. 6 is a left side view thereof;

FIG. 7 is a right side view thereof;

FIG. 8 is an enlarged top plan view thereof; and,

FIG. 9 is an enlarged bottom plan view thereof.

The broken lines depict portions of the mobile phone charger that form no part of the claimed design.
